MIXER TYPE LADLE

Harry L. McFeaters, New Castle, Pa., assignor to
Pennsylvania Engineering Works, a corporation
of Pennsylvania

Application October 24, 1942, Serial No. 463,185

6 Claims. (Cl. 266—39)

This invention relates to hot metal mixer type ladles used on transfer cars for carrying molten metal from the blast furnace to the hot metal mixer or pig casting machine.

Hot metal mixer type ladles of various constructions and designs for use in the make-up of transfer cars have been suggested and many are disclosed in prior art patents.

An object of this invention is to produce a free-flowing mixer type ladle.

Another object of this invention is to produce an improved mixer type ladle having a closure for a portion of the top thereof which provides effective and improved pouring characteristics.

Another object is to produce a shell for mixer type ladles having a substantially semi-closed top, which can be produced from flat metal plate joined together by weld metal into a rigid structure without requiring any complicated metal drawing operations.

A further object is to produce a high capacity mixer type ladle having upper walls that partially close the top of the ladle, and which, with oppositely positioned pouring openings, greatly facilitates pouring and reduces the tendency to skull.

A further object is to provide a design of shell for a mixer type ladle which lends itself to relatively cheap manufacture, from plate metal by simple bending and welding operations.

A still further object is to produce an improved high capacity mixer type ladle with upper walls which partially close in the top and in effect cause such walls to serve as pouring spouts of gradually decreasing volumetric capacity from the longitudinal center of the ladle to the pouring openings in its side walls.

These, and other objects which will be apparent to those skilled in this particular art, I attain by means of the structure described in the specification and illustrated in the drawings accompanying and forming part of this application.

In the drawings:

Figure 1 is a perspective view of a mixer type hot metal ladle embodying this invention;

Fig. 2 is a more or less diagrammatic view in side elevation of the ladle of Fig. 1;

Fig. 3 is a development of cone sections such as used in making up one half of the top portion of the ladle of this invention;

Fig. 4 is a side elevational view of a transfer car carrying a ladle such as disclosed in Fig. 1 with a portion of said ladle broken away for the purpose of illustration;

Fig. 5 is an end elevational view of the car and ladle of Fig. 4;

Fig. 6 is a perspective view of a modified form of mixer type hot metal ladle embodying this invention; and

Fig. 7 is a more or less diagrammatic view in side elevation of the modified ladle of Fig. 6.

Referring first to the form of ladle of Figs. 1 to 5 inclusive, the ladle shell comprises a main or central portion which is substantially U-shaped in transverse section, end portions which are formed as frustums of cones and an upper portion which partially closes in the top of the ladle and is formed as sections of cones of steeper angle than that of the end sections.

The straight walls 10—10 of the central portion join the semi-cylindrical bottom 11 of such portion opposite the longitudinal center of the ladle as shown in the drawings. Walls 10—10 gradually decrease in width from the semi-cylindrical bottom portion to their tops as shown in Figs. 1, 2 and 4. At their widest part, these walls are slightly narrower than the semi-cylindrical bottom portion, and thus form offsets 12—12.

Each wall 10 at its top is provided with a pouring opening 13 which is preferably curved and provided with an outwardly extending lip 14.

Each end portion 15 is formed as the frustum of a cone having its apex positioned at point a. A circular plate 16 forms the top of each such frustum, and encircling the top or outer end of each such frustum is a built-up trunnion pad 17 which is provided with the usual trunnions 18, 19 and 20. These pads are preferably secured in place by means of rivets 21, although if preferred the trunnion pad may be welded in place.

The top of the ladle shell is partially closed in by two cone sections each of which as an entirety is numbered 22. A development of one of these sections is illustrated in Fig. 3, and each such section is preferably built up from four pieces of flat plate such as pieces 23, 24, 25 and 26. These are welded together and then bent to form sections of a cone having its apex at b, which, as will be seen, is further removed from the center of the ladle than apices a—a.

Each cone section 22 is joined by weld metal, to one edge of each wall 10 of the central portion, to offset 12, and to the upper half of the base of the cone frustum adjacent thereto. The lower half of the base of each cone frustum is joined by weld metal to the semi-circular bottom portion of the central shell section.

The inner edge 27 of the top opening of the ladle shell is formed by a strip of plate metal which is welded to the under side of section 22 along its inner edge and forms a retainer for the refractory lining.

The semi-circular part of the central portion is provided with oppositely positioned lugs 28 to which a crane hook can be attached for tilting the ladle toward either side about trunnions 18 or 20, as the case may be.

It will be apparent that when the ladle is tilted toward either side for the purpose of discharge-

ing molten metal therefrom, the upper part of the down tilting side, from the center of the ladle to the pouring opening on that side, serves as a spout which gradually decreases in size from the ladle center to the pouring opening.

It will also be apparent that such spout is formed of three walls that converge to the pouring opening and are free of projections and pockets which might cause eddies in the flowing metal, or obstruct such flow and have a tendency to cause skulling.

The ladle shell of the modified form of Figs. 6 and 7 comprises a main or central section which is substantially U-shaped through any transverse section thereof, end portions which are formed as frustums of cones and an upper portion which partially closes in the top of the ladle and is formed as sections of cones of steeper angle than those of the end sections.

Walls 30-30 of the central portion are curved outwardly from side to side and join the ends of the central section, which section at its bottom 31 is semi-barrel shaped, as shown in Figs. 6 and 7 of the drawings. Walls 30-30 gradually decrease in width from the semi-barrel shaped bottom portion to their tops as shown in Fig. 6. At their widest part, walls 10 are slightly narrower, from side to side, than the bottom portion 31 and thus form offsets 32.

Each wall 30 at its top is provided with a pouring opening 33 which is preferably curved and provided with an outwardly extending lip 34. Each end portion 35 is formed as the frustum of a cone having its apex positioned at point c. A circular plate 36 forms the top of each such frustum.

Circular plates 36 as well as the plate metal from which each end section 35 is formed, is preferably of much heavier gauge than the plate from which the central section is formed, since 40 the end sections carry a built-up structure of which trunnions 37, 38 and 39 form part. The top of the ladle, in the modified form, is partially closed by two cone sections similar to those employed in the form of Figs. 1-5, inclusive, and Fig. 3 can be taken as a development of a section similar to one of these sections. As far as the top of the modified form of ladle is concerned, it is similar to the top of the form of Figs. 1-5 inclusive, except that walls 30-30 in which the pouring openings are formed and which form part of the ladle top, are outwardly curved or bowed from side to side.

The ladle of both forms is supported in position on supports 40 which form part of a transfer car of any suitable construction and such as is more or less diagrammatically illustrated in Figs. 4 and 5.

The ladle shell of both forms is provided with a suitable refractory lining 41 and because of the form of the shell, this may be made up largely of standard refractory blocks, or bricks or if desired, the lining may be made of molded refractory material.

Having thus described my invention, what I claim as new and desire to secure by Letters Patent is:

1. In a mixer type ladle, a side wall which is substantially straight from its longitudinal central portion to its top, has a pouring opening in its top and from the ends of said central portion to said pouring opening is of decreasing

width, and top walls which join said side wall along its portion of decreasing width, encloses part of the ladle top, and, with said side wall forms a pouring spout of decreasing size which 5 extends from the longitudinal center of the ladle to said pouring opening.

2. In a mixer type ladle, parallel side walls which are substantially straight above the longitudinal central portion of the ladle, each substantially straight wall having a pouring opening in its top, and each such substantially straight portion being of decreasing width from its bottom to its top, and top walls which join such substantially straight parallel walls along their portions of decreasing width, enclose part 15 of the ladle top, and with such side walls form opposed pouring spouts which decrease in size from the longitudinal center of the ladle top to said pouring openings.

3. A shell for a mixer type ladle comprising a central or main portion which is substantially U-shaped in transverse section with the straight legs thereof tapered from the curved bottom portion to the top thereof and provided with pouring openings in such tops, end portions of frusto-conical form, and portions intermediate such end portions and the tapered parts of said straight legs; said intermediate portions enclosing part of the top of the ladle, and with said end portions and said straight legs forming spouts which decrease in size from the center of the ladle to said pouring openings.

4. In a mixer type ladle, a side wall which extends substantially vertically from its longitudinal central portion to its top, has a pouring opening in its top, and, from the ends of said central portion to said pouring opening is of decreasing width, and top walls which join said side wall along its portion of decreasing width, encloses part of the ladle top, and, with said side wall forms a pouring spout having its greatest width substantially equaling the greatest width of such side wall, and which decreases in size from the ends of such side wall to such pouring opening.

5. A mixer type ladle comprising a central or main section having a semi-barrel shaped bottom portion, substantially vertically extending sides which extend above said bottom portion, 50 decrease in width from said bottom portion to their tops and have pouring openings in their tops, end walls of frusto-conical form, and top walls which partially close the top of the ladle, are formed as sections of cones, and which, with 55 said end walls and said substantially vertical walls, form spouts that extend from the longitudinal center of the ladle to such pouring openings.

6. In a mixer type ladle, a substantially U-shaped central section having pouring openings in the top of the straight legs thereof; said straight legs being of decreasing width from the curved part of the central section to said pouring openings, end portions which connect with 65 the curved part of the central section, and conical walls which join the upper half of each end portion and the tapered part of said legs, and which, with end portions and said legs form opposed pouring spouts, which are free from 70 obstructions.

HARRY L. McFEATERS.
